George G. Brown,
INVENTOR

BY *Victor J. Evans*
ATTORNEY

William H. Collison
WITNESS:

UNITED STATES PATENT OFFICE.

GEORGE G. BROWN, OF HUNTINGTON, WEST VIRGINIA.

HEATER.

Application filed July 13, 1923. Serial No. 651,341.

To all whom it may concern:

Be it known that I, GEORGE G. BROWN, a citizen of the United States, residing at Huntington, in the county of Cabell and State of West Virginia, have invented new and useful Improvements in Heaters, of which the following is a specification.

This invention aims to simplify the general construction of heating apparatus, of the character adapted for use in a fire place, so that such heaters can be manufactured and sold at a very nominal cost, within the financial reach of all, and at the same time supply the maximum amount of heat with the consumption of a minimum amount of fuel.

In carrying out the invention, I construct a fire box in a manner to permit of its use in a fire place of any known construction, although it is susceptible for use in the capacity of a stove, a stove body or housing being provided for this purpose, which housing is made in separable parts and capable of being quickly and conveniently assembled for use.

One of the chief characteristics of the present invention resides in providing a heater susceptible of adjustment so that it can accommodate itself to fire places of different dimensions, the heater including a fire box wherein the rear wall is made up of adjustable sections so that the degree of inclination of these sections can be varied in accordance with the particular character or size fire place in which the heater is used, whereby the heat can be directed or thrown into the room and thus eliminate the objection with most heaters of this general character, of allowing the heat to escape through the chimney.

Other objects and advantages of the invention will appear when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a front elevation showing the heater positioned within a fire place.

Figure 2 is a sectional view taken on the

line 2—2 of Figure 1, looking in the direction of the arrows. 55

Figure 3 is a sectional view taken on the line 3—3 of Figure 2, looking in the direction of the arrows.

Figure 4 is a sectional view taken on the line 4—4 of Figure 2, looking in the direction of the arrows. 60

Figure 5 is a perspective view of one of the side walls of the fire box.

Figure 6 is a fragmentary perspective view of one of the sections of the rear wall 65 of the fire box.

Figure 7 is a fragmentary rear elevation of the upper portion of the frame like structure.

Figure 8 is a sectional view taken on the line 8—8 of Figure 7, looking in the direction of the arrows. 70

The heater forming the subject matter of the present invention embodies amongst other features a frame like structure designed to support a fire box primarily intended to be arranged within the ordinary well known fire place as shown in Figure 1. This frame like structure embodies but few parts so that it can be manufactured and sold at a very nominal cost, thus making it possible for those in moderate circumstances to make use of the invention. As illustrated, this frame like structure includes opposed side walls 10, which supports a hood 11 including sections 11' adjustable towards and away from each other. The side members 10 are of course provided with flanges 12 at their forward edges to add to the ornamental quality of the heater as a whole when the latter is arranged within the fire box as shown in Figure 1. The supporting structure may be formed from any suitable material and may also vary in size and configuration without departing from the spirit of 95 the invention. However, when the frames are formed in sections to permit of the adjustment, the side members 10 are held together adjacent their upper and lower ends by sectional rods as clearly shown in Figure 4. Each rod of course includes sections 13 and 14 respectively, the adjacent ends of

which are reversely threaded to accommodate a turn buckle 15. Manifestly, by turning these buckles in the proper direction, 105 the side members of the frame can be moved

toward or away from each other as the occasion requires. To close the joint or space between the hood sections 11', when the sections of the frame are moved away from each other, I make use of a plate 16, the latter being curved at its upper end to conform to the curvature or configuration of the hood 11, which structure is clearly shown in Figure 8. This plate 16 is positioned 5 with relation to the side members 11 as shown by dotted lines in Figure 7, and supports bolts 17 which project forwardly from said plate, each bolt passing through a slot 18 formed in the adjacent hood sections 11'. 10 15 This construction permits of an adjustment of the side members 10 with relation to the plate 16, the parts being held fixed relatively in their adjusted positions by means of winged nuts 18 with which the bolts 17 are 20 equipped. This of course is the preferred manner of providing for the adjustment between the side members 10 of the frame, it being understood that other methods may be resorted to without departing from the 25 spirit of the invention.

The frame as above stated is adapted to support a fire box including opposed side walls 19, and a back wall including upper and lower sections 20 and 21 respectively. 30 These walls, of course, are preferably constructed from fire clay although any suitable material may be employed. In this connection it is pointed out that these sections are made in various lengths to permit the heater to be used in conjunction with fire places of various sizes. A grate of any suitable construction is arranged within the fire box and is indicated at 22. Carried by the side members 10 of the supporting frame 35 at the upper and lower edges thereof are lugs 23, the lugs being designed to engage the adjacent edges of each side wall 19 of the fire box to support the wall on the frame like structure. Then again, each side wall 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 slotted guide 24 and as the upper section is moved forwardly the packing element 35 contacting with the side walls 36 frictionally engage the side walls and lock the back wall 5 in an adjusted position.

While it is believed that from the foregoing description, the nature and advantages of the invention will be readily apparent, I desire to have it understood that I 10 do not limit myself to what is herein shown and described and that such changes may be resorted to when desired as fall within the scope of what is claimed.

Having thus described the invention, I 15 claim:

1. A heater of the character described comprising a support, including brackets, a fire box engaged by said brackets and mounted on the support, said fire box including opposed side walls and a back wall embodying oppositely inclined superimposed sections, means for holding and adjusting the sections, the bottom edge of the lower section being rounded to accommodate 25 itself to said brackets, the upper edge of said section being recessed, and the lower edge of the upper section being formed with a rounded surface and fitted in said recess, whereby said sections may be adjusted with 30 a minimum of friction to vary the degree of inclination thereof for the purpose specified.

2. A heater of the character described comprising a support, a fire box including opposed side walls mounted on the support, and a back wall embodying oppositely inclined superimposed sections, means for mounting said sections for pivotal movement whereby the degree of inclination of 40 the sections can be varied for the purpose specified, the upper edge of the lower section being recessed, and the lower edge of the upper section being rounded to fit in said recess, and means for holding and adjusting the sections.

3. A heater of the character described comprising a support, a fire box including opposed side walls, and a back wall, lugs carried by the support and arranged to engage the opposite ends of said side walls to hold the latter on the support, said back wall including oppositely inclined superimposed sections arranged between the side walls, said sections being mounted on the support for pivotal movement, and having the adjacent edges interfitted, whereby the degree of inclination of said sections may be varied, means for holding and adjusting the sections, the opposed side edges of the

back wall being recessed, and packing arranged in said recesses and bearing against the side walls of the fire box.

4. A heater of the character described comprising a support, a fire box including opposed side walls, and a back wall embodying oppositely inclined superimposed sections having their adjacent edges interfitted, reinforcing strips secured to the rear surface of the respective sections, the adjacent ends of said reinforcing strips being hinged- 65 ly connected together, means for supporting the other ends of said strips for pivotal movements whereby the sections of the back wall can be adjusted to vary their degree 70 of inclination, and means for holding said sections to the back wall.

5. A heater of the character described comprising a support, a fire box including opposed side walls, and a back wall embodying oppositely inclined superimposed sections, means for mounting said sections on the support for pivotal movement, and the upper edge of the lower section being recessed, the lower edge of the upper section being rounded to fit in said recess, and to 80 permit said sections to be adjusted to vary the degree of inclination thereof, a substantial U-shaped element associated with both 85 of said sections and projecting in advance of the fire box, whereby the sections and back 90 wall are held together.

6. A heater of the character described comprising a frame like supporting structure including separable sections, a fire box mounted on said structure and including opposed side walls and a back wall, and said back wall including oppositely inclined relatively movable sections, whereby the degree 95 of inclination of said sections may be varied, and means for holding and adjusting the 100 sections.

7. A heater for fire places comprising a frame like supporting structure including a back and separable side sections, means connecting said sections, a hood supported by the side sections and including sections adjustable towards and away from each other, a plate arranged between said sections adjacent the upper edges thereof, bolts projecting from said plate, said sections 105 having elongated slots receiving said bolts, winged nuts associated with said bolts for holding the sections fixed relatively to the plate in any given position, and a fire box mounted on the supporting structure and 110 including a rear wall having oppositely inclined sections.

GEORGE G. BROWN.
